UNITED STATES PATENT OFFICE.

GEORGE W. STETSON, OF HINGHAM, MASSACHUSETTS.

WATER-LEVEL CONTROLLER.

1,418,845.

Specification of Letters Patent. Patented June 6, 1922.

Application filed September 6, 1917. Serial No. 190,094.

To all whom it may concern:

Be it known that I, GEORGE W. STETSON, a citizen of the United States, residing at Hingham, in the county of Plymouth and State of Massachusetts, have invented certain new and useful Improvements in Water-Level Controllers; and I do hereby declare the following to be a full, clear, and exact description of the invention such as will enable 10 others skilled in the art to which it appertains to make and use the same.

The present invention relates to water level controllers and more particularly to controllers of this type employed in connection with 15 steam boilers.

The object of the present invention is to improve and reorganize feed water controllers in a manner to increase the sensitiveness of control and ensure a continuous feed to 20 a boiler governed by the demand for steam and independent of the temperature of the water or steam.

With this object in view the several features of the invention consist in certain novel 25 features of construction, combinations and arrangements of parts hereinafter described and claimed, the advantages of which will be obvious to those skilled in the art from the following description.

30 In the accompanying drawings, Figure 1 represents an elevation of the controller with the casing cut away to illustrate clearly the various working parts; and Fig. 2 is a detail illustrating a plan view of the valve lever and connected parts.

The present invention contemplates the provision of a float contained in the usual chamber connected with the steam boiler and operating a feed valve which controls the 40 supply of water to the boiler. It is desirable that the connections between the float and water valve shall be freely movable in order that slight changes of level in the float chamber shall immediately vary the position of the valve. To this end a float lever is supported between its ends upon a fixed fulcrum and is connected to the upper end of a valve rod through short links. The valve rod is constrained to move in a rectilinear 50 path and the link connection immediately adjacent to the fulcrum of the float lever permits the proper movements to be imparted to the valve rod by the float without binding or cramping the rod in its guides. 55 The weight of the float and connected parts together with the liquid contained therein

is balanced by suitable counter-weights supported upon the end of the lever opposite the float and as the connection with the valve rod is in close proximity to the fulcrum of the lever it will be obvious that a slight pressure exerted upon the float and due to changes in water level outside of it in either direction will suffice to impart the proper movements to the valve rod.

As shown in the illustrated embodiment of the invention the float chamber is contained within a casing 10 and is provided with a float 11 supported upon the outer end of a float lever 12 which is fulcrumed upon the casing at 13 and is connected with the upper end of a valve rod 14 upon the opposite side of the fulcrum. The float lever conveniently comprises a member 15 having trunnions 16 which are journaled in opposite sides of the casing and a tubular portion 18 in which the end of a float rod 19 is threadedly received and secured in position by a clamp nut 20. The member 15 of the float lever is pivotally connected with the upper end of the valve rod 14 through a pair of short links 24 which are connected at their opposite ends to pins 25 and 26 secured, respectively, in the member 15 and the upper end of the valve rod. A valve casing 30 is secured to the under side of the float casing 10 and is provided with upper and lower valve sleeves 32 and 33 through which pistons 35 carried by the valve rod 14 move vertically. These piston valves 35 co-operate with triangular ports 36 formed in the valve sleeves to control the flow of water through the valve. The upper and lower sleeves are conveniently formed in a single valve cage threadedly connected to the casing 30 at 37 and provided with vertical webs 38 which connect the two sleeves. With this construction a vertical movement of the valve rod causes a gradually increasing amount of water to flow through the valve 100 ports as they are uncovered by the co-operating pistons. The cage 37 is also provided with depending arms 40 which support a bearing ring 41 in which an enlarged lower end 42 of the valve rod is slidingly received. 105 This construction forms a guide for the lower end of the valve rod and ensures that the valve rod and piston valves carried thereby shall be properly centered with relation to the valve sleeves. The feed water 110 is conducted into the valve casing through an intake passage 43 and is conducted from

the valve casing to the boiler through a passage 44. In order to elevate the valve rod and permit the boiler to be filled with water when subjected to a hydrostatic pressure, a 5 valve lifter 48 is positioned beneath the lower end of the valve rod and is supported upon the upper end of an adjusting rod 49 threadedly connected with the lower portion of the casing. The upper end of the valve 10 rod passes loosely through a sleeve 50 threaded within a bushing 51 which is in turn threaded in the neck of the valve casing 30. The sleeve 50 forms a guide for the upper end of the valve rod and at the 15 same time prevents the discharge of any substantial quantity of water from the valve chamber into the float chamber although permitting the passage of a small quantity to lubricate the valve rod.

20 The weight of the float 11 and supporting lever together with the liquid contained in the float is accurately balanced by a plurality of weights 53 which are supported upon the end of the float lever opposite the float.

25 Each weight consists of a disk of suitable thickness provided with a radial slot 54 to permit the disk to rest upon the float lever in the usual manner. The disks are retained in position by oppositely disposed collars 55

30 secured to the float lever through a clamp screw 56. The counter-balancing effect of the weights may be conveniently varied by adjusting the position of the weights toward and from the fulcrum 13 of the float 35 lever. This adjustment of the weights is easily secured by the movement of the collars 55 along the member 15. The provision of the hand hole covers 60 and 61 above the weights 53 and the float 11 permits 40 the convenient assembling of the apparatus or the substitution of one part for another when desired.

This construction provides a simple and compact mechanism for accurately controlling the flow of water to a boiler, to maintain a variable level in the boiler dependent on the rate at which steam is being used. The water level in the float chamber is maintained uniform with the level in the 50 boiler through the usual connections 63 and 64 at the bottom and top of the float chamber, respectively.

It is customary in apparatus of this type to provide a sealed float within the float 55 chamber adapted to change its position in accordance with changes of the water level within the chamber. Owing to the pressure within the float chamber it is desirable to provide some means for equalizing the pressure 60 upon the exterior and interior of the float and for this purpose the addition of a small quantity of water to the interior of the float has been suggested in order that the steam generated by this water when the 65 float is in use shall exert the desired pres-

sure upon the inside of the float. Owing to the radiation from the float casing and some slight leakage of water from the valve chamber into the float chamber, and perhaps other causes, the temperature of the water within 70 the float chamber is less than the temperature of the steam at the pressure within the chamber and the temperature of the interior of the float which is immersed in both the water and steam is accordingly less than 75 that of the steam. It is not possible by this means, therefore, to secure a pressure within the float equal to the pressure without the float as the temperature within the float is less than the temperature of the steam in the 80 float chamber. According to the present invention the pressure upon opposite sides of the float is exactly balanced and the objections incident to apparatus of this kind, as above described, are obviated by the employment of an open container which is completely filled with water and the interior of which is in free communication with the float chamber so that the pressure upon the inside and outside of the container is equalized. The fact that the temperature within the container or float is actually less than the temperature of the steam in the float chamber at the same pressure ensures that the water within the container will not be vaporized and any steam which may enter the container will be condensed as water, so that the container is at all times maintained completely full of water. With this construction that portion of the water within the container that is located above the water level in the float chamber adds to the effective weight of the container that is balanced by the counter-weights. When the water level within the chamber drops, therefore, the effective weight of the float is increased, overbalancing the counter-weights to elevate the valve rod. When the water level within the chamber rises, upon the other hand, the effective weight of the container is decreased 95 so that the counter-weights overbalance the container and depress the valve rod. In order to aid in the flow of condensed steam into the container the opening 65 at the top of the container is provided with an outwardly 100 flanged rim 66 arranged to collect the steam and direct it into the container. In other words the float tends to assume a position substantially as shown in the drawings, with the lower half of the container submerged in 115 the water of the float chamber. With this construction the float, owing to the fact that it does not have to withstand unbalanced pressures, may be extremely light, permitting a like reduction in the operating parts. 120

The float is conveniently secured to the end of the valve lever by a pair of straps 70 and 71 looped about the float and secured at their inner ends to a collar 73 threadedly secured to the end of the valve lever. The straps 125

serve to press the float against a seat 74 supported upon the end of the valve lever and shaped in conformity with the curvature of the float.

While it is preferred to employ the specific construction and arrangement of parts shown and described, it will be understood that this construction and arrangement is not essential except so far as specified in the 10 claims, and may be changed or modified without departing from the broader features of the invention.

The invention having been described, what is claimed is:

15. 1. A water level controller, comprising a float casing having a chamber connected with the steam and water spaces of a boiler, a float lever supported within the casing upon a fixed fulcrum, a container completely filled 20 with water and supported upon one end of the lever, a valve rod, means for guiding the valve rod in a rectilinear path, and a link connecting the upper end of the valve rod with the float lever adjacent the fulcrum 25 and upon the opposite side from the container.
2. A water level controller, comprising a float casing having a chamber connected with

the steam and water spaces of a boiler, a float lever supported within the casing upon 30 a fixed fulcrum, a container completely filled with water and supported upon one end of the lever, a counter-weight supported upon the opposite end of the lever, a valve rod having balanced opposed valves mounted 35 thereon, means for guiding the valve rod in a rectilinear path, and a link connecting the upper end of the valve rod with the float lever adjacent the fulcrum and upon the opposite side from the float. 40

3. A water level controller comprising a casing having a float chamber, a steam connection entering the upper portion of the casing, a container filled with water and having an opening in the uppermost portion 45 directly below the steam connection, a feed valve, a vertically movable valve rod, a loose guide for the valve rod between the float chamber and valve chamber which permits cold water from the valve chamber to leak 50 into the float chamber, connections between the valve rod and container, and means for counter-balancing the container and connections.

GEORGE W. STETSON.
